UNITED STATES PATENT OFFICE.

SEDGWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

SWITCH PROTECTION FOR BLOCK-SIGNAL SYSTEMS.

Application filed November 3, 1920. Serial No. 421,453.

To all whom it may concern:

Be it known that I, SEDGWICK N. WIGHT, citizen of the United States, residing at Rochester, in the county of Monroe and 5 State of New York, have invented certain new and useful Improvements in Switch Protections for Block-Signal Systems, of which the following is a specification.

This invention relates to block signaling 10 systems for railroads, and more particularly to the protection of outlying switches in block signal territory.

In accordance with the present practice with which I am familiar, switch indicators are provided at the outlying switches in block signal territory for the purpose of informing the trainman when it is safe to open the switch. The protection afforded by such switch indicators evidently depends 20 upon the care observed by the trainman in obeying the indications. If he is thoughtless or careless, it is possible for him to open a switch when a train is approaching at high speed on the main track, with the result 25 that an accident occurs. In accordance with the present invention it is proposed to provide a check on the human factor by employing a switch lock in connection with the switch and by controlling this lock in such 30 a way that the trainman cannot open the switch except when it is safe to do so.

The general objects of the invention are to provide an arrangement of devices and controlling circuits for switch locks which 35 will give desired protection without interfering with normal train movements or causing unnecessary delay. Other specific objects and advantages of the invention will appear as the description progresses.

In describing the specific embodiments of 40 my invention in detail, reference will be made to the accompanying drawings, in which—

Figure 1 is a diagrammatic view showing 45 my improved system for the control of switch locks applied to an outlying switch on a stretch of double track;

Fig. 2 is a view, partly in perspective with parts broken away and spread apart for

clearness, which shows one form of an electrically operated switch lock adaptable for use in connection with my invention; 50

Figs. 3 and 4 when placed end to end, with Fig. 3 on the left, show diagrammatically a stretch of single track between two passing sidings, with the signals, relays and controlling circuits therefor constituting a block signal system, commonly known as an absolute permissive block system, suitable 55 for single track operation of trains, together with an outlying switch equipped with my improved switch lock control system;

Fig. 5 is a view similar to Fig. 4 showing a modified arrangement of the controlling 60 circuits for the switch lock for single track roads; and

Fig. 6 illustrates a still further modification.

In connection with my invention I employ an electrically operated switch lock which may be of any suitable construction. One type of such a switch lock is illustrated in a diagrammatic way in Fig. 2. Referring to Fig. 2, a lock rod 11 is connected in the usual way to the movable switch points 12—12^a and is provided with a hole to receive a lock bolt 13 when the switch points are in the normal position shown, that is, are lined up for the main track. 70 The lock bolt 13 is supported and guided by a suitable casing or framework 14, and is pivotally connected to a link 15. This link 15 is pivotally connected at its upper end to a crank arm 16 secured to a shaft 17. To the shaft 17 is fastened a lock plate 18 and an operating handle 19. The lock plate 18 is formed with a shoulder for cooperating with a lock dog 20 carried by an armature 21. This armature 21 is raised 75 when the coils or windings 22 of a lock magnet L are energized. The armature 21 is also connected by a rod 23 to a shaft 24 which carries the usual miniature semaphore or indicator 25. In practice, the operating parts of the switch lock are enclosed in a protecting casing, a portion of which is shown at 26. 80 85 90 95

The switch points 12—12^a which are in practice moved by some suitable switch stand or the like (not shown) cannot be shifted from the normal position shown until the 5 lock bolt 13 is raised. This lock bolt is raised to release the switch points by turning the handle 19, and if the lock magnet L is de-energized, the lock dog 20 cooperating with the plate 18 prevents such movement of the 10 handle 19. In short, the lock magnet L must be energized before the switch can be operated. When the lock is released, this is indicated by the position of the indicator 25, and the handle 19 may be swung to lift 15 the lock plunger 13. In the type of electric lock illustrated, and which is preferably employed, this handle 19 is moved so as to bring the crank 16 and link 15 on upper dead-center, so that the lock plunger is held 20 up, while the trainman throws the switch points. In order to assure the replacing of the lock plunger, the door giving access to the handle 19 is, in the type of switch lock referred to, provided with lugs and recesses 25 (not shown) in such a way that the door cannot be closed if this handle is left in its upright position. If, however, the handle is partly turned back to the normal position shown, sufficient to bring the link 15 beyond 30 dead-center, then the door can be closed and locked. In ordinary usage, the trainman, after having unlocked and opened the switch, restored the handle 19 part way to its normal position, with the lock plunger 35 13 resting upon the lock rod 11, and closes and locks the door, and as soon as the switch points are restored to the normal position, the lock plunger 13 drops by its own weight into the hole in the lock rod 11, the parts 40 being thus restored to normal without special manipulation by the trainman. It is to be understood, however, that this type of electric lock described is merely illustrative, and various other expedients may be employed 45 for compelling manipulation of the lock in a certain manner in order to safeguard the handling of the switch. For the purpose of explaining the present invention, it is not necessary to consider the various modifications of the electric lock structure that 50 may be employed.

In Fig. 1 I have shown a system for the control of the switch lock in its simplest form applied to a stretch of double track 55 over which traffic normally moves in one direction from left to right, as indicated by the arrow. The track rails 27 of this stretch are divided by insulated joints 28 into blocks or track sections, as D, E, F in the usual 60 way, each of these track sections being provided with the usual track battery 29, and a track relay, as 30 to 34 inclusive. Traffic over this stretch is governed by signals 35 to 38 inclusive. The line relays and controlling circuits for these signals, which may

be arranged in accordance with any of the approved block signal systems, have not been shown in order to avoid unnecessary complication of the drawing. To illustrate the present invention it is assumed that 70 there is an outlying switch leading to a siding S—D in the block F between the signals 37 and 38; and in accordance with this invention, the block F, where this outlying switch is located, is provided with a short 75 track section F² adjacent to said switch. A switch box, having contacts 39 shown conventionally, is connected to the points of the switch in the usual way. To avoid complication in illustration, all parts of the 80 switch lock shown in Fig. 2 have not been illustrated in Fig. 1, but merely the lock magnet L, lock dog 20 and plate 18. In connection with the control of the lock magnet L, I employ any suitable form of a time 85 element relay T. Various types of time element relays, well known in the art, are suitable for this purpose. One device of this nature is disclosed, for example, in patent to R. C. Leake, No. 1,320,247, October 28, 90 1919. For simplicity I have illustrated the relay T as comprising a movable armature or contact finger 40 connected to a suitable dashpot or time control device 41, so that when said relay is energized, it will close 95 its contacts after the lapse of a predetermined time for which the device is set. In addition to the switch lock and time element relay T the improved system of switch protection includes a push button PB or other 100 suitable circuit controlling means, adapted to be operated by the trainman. This push button is shown diagrammatically and comprises a number of contact fingers 42, 43 and 44 which cooperate with suitable fixed contacts indicated conventionally as arrows. This push button PB is located near the switch lock, preferably in the same casing, so that it may be held down at the same 105 time the handle 19 is operated. This push button is preferably of the spring return type, although switches or other suitable circuit controlling devices may be employed. For simplicity the circuits involved in the 110 invention have been illustrated in a conventional manner. The batteries or other sources of current employed in practice are not illustrated, but the connections to the terminals of these batteries are indicated conventionally by the notations B and C, it 115 being understood that when a partial circuit as shown can be traced from B to C, current will flow in this circuit. The controlling circuit for signal 37, which is only in part illustrated, is controlled by the track relays 32, 33 and 34 of the track sections F¹, F² and F³ constituting the block between the signals 37 and 38. This controlling circuit also includes the 120 switch box contacts 39, which are open when 125

the switch is shifted from the normal position to the reverse position. This controlling circuit for the signal 37 passes through the normally closed contacts 42 on the push button PB. Thus, if a train is in any part of the block protected by signal 37, or if the push button PB is operated, or if the switch is open, the controlling circuit for signal 37 is broken and said signal is put to the horizontal or stop position.

The lock magnet L may be energized by any one of three circuits when the push button PB is operated. One circuit is from battery B through contacts 43 of the push button, wire 45, lock magnet L, wires 46 and 47, back contact of armature 48 of the track relay 33 connected to short track section F², and thence through other wires and connections (not shown) to the other terminal of the battery. Another circuit for energizing the lock magnet L is from battery B, contacts 43 of push button PB, wire 45, lock magnet L, wires 46 and 50, front contact of armature 51 of track relay 32, wire 52, front contact of armature 53, of track relay 31, wire 54, and front contact of armature 55 of relay 30. Another circuit for energizing the lock magnet is from battery through contacts 43 of the push button PB, wire 45, lock magnet L, wires 46 and 49, and contacts 40 of the time element relay T. The time element relay T is energized by a circuit which may be readily traced through contacts 44 of the push button PB when said push button is operated.

The operation of the system shown in Fig. 1 is as follows: Assume that there is no train in the blocks D and E or in track section F. When a trainman desires to open the switch leading to the siding SD, he operates the push button PB, opening contacts 42 and closing contacts 43-44. The opening of contact 42 breaks the control circuit for signal 37 and causes this signal to assume the stop position. This in turn results in putting the signal 36 to the caution position by virtue of the usual control circuits (not shown). This results in blocking train movements toward the switch. Since it is assumed that the blocks D, E and track section F¹ are not occupied, the circuit through the front contacts of the track relays 30, 31 and 32, hereinbefore traced, is established, and the lock magnet L is energized. This releases the handle 19, so that the trainman may raise the lock plunger 18 and release the switch points. When the switch is opened, the switch box contacts 39 open and keep the signal 37 at stop, so that trains approaching the switches are blocked so long as the switch remains open. When the switch is reclosed, the lock plunger 18 drops in place and locks the switch points, and all the parts and circuits are returned to the normal position shown.

If, however, there should be a train present in the blocks D, E, or the track section F¹, and this train is approaching at speed, then the switch should not be opened, but it may happen that this approaching train is going to make a stop at a station, or take a siding, or for some other reason fail to proceed immediately past the switch, so that there is time for the train on the siding SD to get out on the main track, in which case it is desirable to release the switch lock provided the proper precautions have been taken. These conditions are taken care of by the time element relay T. When the push button PB is operated the energizing circuit for the relay T is closed at the contacts 44, and after the selected time interval for which said relay is adjusted, the contacts of this relay close, establishing a circuit hereinbefore traced for energizing the lock magnet L, regardless of the presence of the train in the blocks D or E. As previously explained, operation of the push button PB puts the signal 37 to stop in the stop position, and the signal 36 in the caution position. If a train is in the block D at the time the push button PB is operated, it will receive a caution indication at the signal 36 and come to a stop at the signal 37 in the regular way. The time interval required for the operation of the relay T is selected or adjusted so that, if the train is beyond signal 36, and the push button PB is operated and the operation of the relay T is commenced, such train will have time enough to either stop before reaching the switch or else get past this switch. Thus, before the lock magnet L can be energized, and the switch lock released, a warning must be given to the train assumed to be on the track section D or E, and sufficient time elapse for this train to stop or proceed by the switch. If desired, a separate switch indicator may be provided according to the present day practice at the switch, so that the trainman can tell if another train is approaching, without being required to operate the push button PB and put the signal 37 to stop, it being evident that it may be objectionable in some cases to put the signal 37 to stop in the face of a train approaching at high speed.

It often happens that a train on the main track will enter the siding SD, and it is necessary to make provision for releasing the switch lock under such conditions. When a train is to enter the siding SD, it pulls up to the switch on to track section F², thereby dropping track relay 33 and closing its back contact, so that the lock magnet L can be instantly energized when the push button is operated. The track section F² is preferably made only a few rail lengths so that a trainman at the switch could not fail to observe a train on this short track section.

From the foregoing it will be observed that the control of the switch lock according to this invention is such that the lock may be released immediately if a train has 5 pulled up to the switch for the purpose of entering the siding, or if there is no approaching train within a certain distance of the switch, this distance being sufficient to bring such approaching train to a stop before reaching the switch. Also, in special 10 cases where it may be desirable to be able to open the switch, although a train is within the limits of protection, the switch lock may be released after a time, this time interval 15 being such that the train, if it continues its movement, will have time enough to get by the switch, or else to stop in obedience to the signals.

In Figs. 3 and 4 there is shown a system of 20 control for the switch lock of an outlying switch on a single track on which traffic is in both directions. In Figs. 3 and 4 there is illustrated in a conventional way a complete system suitable for governing traffic over a 25 stretch of single track between two passing sidings, together with the circuits and devices relating to the control of the switch lock combined with this system. It is to be understood, however, that the particular application shown is illustrative of only one 30 embodiment of the means contemplated by this invention, and that the invention can be applied to single track signaling systems of other types in the same way.

The block signal system shown in Figs. 3 35 and 4 is of the type commonly known as an absolute permissive block system, and is shown and described in detail in my prior Patent, 1,294,736, February 18, 1919, so that 40 for the purpose of explaining the present invention, only a brief description of this APB system will be given.

Figs. 3 and 4 are to be arranged end to 45 end with Fig. 4 on the right. The stretch of track between the two passing sidings PS and PS¹ is divided in the usual way into a number of track sections, which have been designated *a*, *b*, etc. Each of these track sections is provided with the usual track battery and track relay. In order to avoid complication of the drawing, these track relays have been illustrated conventionally as dash 50 lines connected to the track rails, the contact fingers of each track relay being shown in conjunction with these dash lines. Trains travel over this stretch of single track in both directions, as indicated by the arrows X and Y. Signals 1, 2, etc., are located at intervals along the track. These signals 55 may be any well known or suitable construction. The signals 2 and 7 governing the movement of trains in opposite directions into the stretch of single track between the sidings, are of the type commonly called absolute signals. These signals are usually in

practice made distinguishable from the other signals by having square ended blades and marker lights.

The system in a general way is made up of a number of units, and for convenience 70 the relays and other devices of each unit are given the same reference characters with exponents corresponding to the signal associated with that unit. At each signal is a line relay, as H², a stick relay, as S², and a local battery. In some cases the circuits connected to the local batteries are entirely local, and in this case these circuits are designated conventionally as terminating at symbols B and N. In other cases the local batteries transmit current from one signal location to another, the return connection in each instance being made by a common wire extending along the track, and in this case, the circuits are indicated conventionally as terminating at the symbols B and C. Operated by some of the signals is a pole changer, as P². This pole changer, being of well known construction, has been illustrated conventionally, and it is understood 90 that it is coupled in some suitable way to the operating mechanism of the corresponding signal so as to be shifted from the position shown to the opposite position when the signal changes from its caution to the 95 stop position. The signals are also provided with suitable circuit controllers, as O², which have been shown in accordance with established convention. These circuit controllers are closed when the corresponding 100 signal is in the 90° or proceed position, and for part of its movement (usually about 50°) toward its zero degree or stop position.

To illustrate the nature and mode of operation of my improved system of control 105 for switch locks, it is assumed that there is an outlying switch somewhere in the stretch of single track which leads to the siding SD. This switch may be located at any point in the stretch, and the same principles 110 of control hereinafter explained may be employed by making appropriate changes in the wiring connections.

In considering the devices and circuits 115 constituting the present invention, it is desirable to explain briefly the operation of the APB system, reference being made to my prior patent above mentioned for a fuller explanation of some of the special features and advantages of this type of system. Before taking up the description of 120 this operation, it is convenient to point out some of the typical circuits involved in this operation. The indications of each signal are controlled by neutral and polar contacts 125 on the corresponding line, relay. For example, referring to the signal 2, the 90° controlling circuit (which puts the signal in the 90° or proceed position) may be traced as follows: from battery through 130

neutral armature 70 of the line relay H^2 , wires 71 and 72, polar armature 73, wires 74, signal 2 to N, signifying a connection to the other terminal of the battery. The circuit for controlling the 45° or caution position of the signal 2 may be traced from battery B, neutral armature 70, wires 71 and 75 and signal 2. The circuit controlling the line relay H^2 is representative of the controlling circuits for the other line relays. This circuit may be traced as follows: commencing at the connection to the common wire C, relay H^2 , wire 76, front contact 77 of the track relay of section b , wire 78, front contact 79 of the track relay of section c , wire 80, back contact 81 of stick relay S^2 , wires 82 and 83, front contact 84 of line relay H^4 , wires 85 and 86, and through the pole changer P^4 to the common wire C. The front contact 84 of the line relay H^4 is shunted when the stick relay S^4 is energized, said shunt comprising wires 83 and 87, front contact 88 of the stick relay S^4 , and wires 89 and 85. From the foregoing circuit, it will be evident that the line relay H^2 is deenergized when (1) either of the track sections b or c is occupied, (2) stick relay S^2 is energized, (3) line relay H^4 is deenergized, and stick relay S^4 is not energized at the time. The line relays of signals 4 and 6 are controlled by the line relay of the signal next in advance, in the same way.

The stick relay at each signal is energized when a train passes that signal in the direction of traffic governed thereby, and is maintained energized until such train has passed out of the track sections governed by that signal. For example, the pickup circuit for the stick relay S^4 may be traced as follows: from battery through circuit controller O^4 , wire 90, back contact 91 of track relay section d , wires 92 and 93, relay S^4 , to the other terminal of the battery. When a train traveling from left to right, enters the track section d , back contact 91 of track relay of that section is closed, thereby establishing this pickup circuit during the time the signal is moving to its stop position. The stick circuit for the relay S^4 may be traced as follows: commencing at battery B, back contact 94 of line relay H^4 , wire 95, front contact 96 of relay S^4 , and wires 97 and 93 through said relay to the other terminal of the battery. Thus, the stick relays, when once energized, are maintained energized so long as the corresponding line relay is de-energized.

Assume a train enters the stretch of single track from the siding PS, traveling from left to right in the direction indicated by arrow X. The entrance of this train into track section b drops the line relay H^2 , and thereby putting the signal 2 to stop. At the same time stick relay S^2 is energized, so as to modify the control of the signal (not

shown) in the rear in the manner herein-after explained. The dropping of the track relay of track section b also drops line relay H^3 , and puts signal 3 to stop. The dropping of line relay H^3 in turn causes dropping of line relay H^5 , which in turn drops line relay H^7 , thereby putting all of the opposing signals 3, 5 and 7 to stop. The starting signal 7 being at stop, blocks the entrance of another train into the opposite end of the stretch of single track. As the train proceeds into track section c , the same conditions are maintained. When this train enters track section d , signal 4 is put to stop, and stick relay S^4 picked up. The picking up of stick relay S^4 shunts the front contact 84 of line relay H^4 , so that as soon as the train leaves the track sections b and c , line relay H^2 is picked up, and the signal 2 allowed to assume its 45° or caution position, the polarity of the control circuit for this line relay having been changed by pole changer P^4 when signal 4 went to stop. When the train passes beyond signal 3, this signal clears, providing there is no following train within the limits of its control. As the train proceeds, a similar operation is repeated, the several signals behind this train assuming the caution position and then the proceed position. The same operation occurs for movements in the opposite direction from right to left.

The controlling circuits for the lock magnet L in Figs. 3 and 4, while similar in principle to those already described in connection with Fig. 1, are somewhat different because trains may approach a switch from either direction. The switch is provided with switch box contacts 98 and 99 in the usual way, and the push button PB is provided with two normally closed contacts 100 and 101 and two normally open contacts 102 and 103. The controlling circuit for line relay H^6 of signal 6 (which can be readily traced from analogy to the circuits already discussed) is taken through the switch box contact 98 and the push button contact 100, so that when said push button is operated, or the switch opened, the signal 6 is caused to assume the stop position, the signals 4 and 2 in turn being caused to move to the stop position. Similarly, the control circuit for the line relay H^7 of signal 7 is taken through the push button contacts 101 and the switch box contacts 99 for the same purpose. The lock magnet L may be energized by any one of three circuits, similar to those already described in connection with Fig. 1. When the short track section g (corresponding to track section F^2 in Fig. 1) is occupied, and the push button PB is operated, then magnet L is energized by a circuit which may be traced as follows: commencing at B, back contact 104 of the track relay of section g , wires 105, 106, lock mag.

net L, wire 107, push button contact 103, wires 108 and 109 and back contact 110 of the same track relay to N.

A train approaching the switch from either direction controls another energizing circuit for the lock magnet L, when said train is between track section c next in the rear of signal 4, and track section k, next in the rear of signal 9. A train receding

from the switch, however, does not prevent energization of the lock magnet L, for reasons about to be explained. The circuit for controlling the lock magnet L, dependent upon the direction of movement and location of trains on the trackway, comprises a main circuit and a number of multiple branches. The main circuit may be traced as follows: commencing at B (near signal 3) through front contact 111 of the track relay of section c, wires 112 and 113, front contact 114 of track relay of section d, wire 115, front contact 116 of track relay of section e, wires 117 and 118, front contact 119, track relay of section f, wires 120 and 106, lock magnet L, wire 107, push button contacts 103, wires 108, 121 and 122, front contact 123 of track relay section h, wire 124, front contact 125 of track relay of section i, wires 126 and 127, and through front contact 128 of track relay of section k, to N. Front contact 111 is shunted, when stick relay S⁸ is picked up, by a shunt comprising wire 129, front contact 130 of said stick relay, and wires 131 and 112. When stick relay S⁵ is picked up, wire 118 is connected directly to battery along wire 132 and front contact 133 of said relay. Similarly, when stick relay S⁸ is picked up, wire 121 is connected direct to the other terminal N of said battery through wire 134 and front contact 135 of said relay; and when stick relay S¹⁰ is picked up wire 126 is connected to N over wire 136 and front contact 137 of said relay.

The third energizing circuit for the lock magnet L is established when the push button PB is operated, and the time element relay T has closed its contacts 138 and 139. This energizing circuit may be traced as follows: commencing at battery, contact 139, wires 140 and 106, lock magnet L, wire 107, push button contact 103, wires 108 and 141 and contact 138 of relay T to N. The time element relay T is energized when the push button P is operated through contact 102, by means of a circuit readily traced on the drawing.

The operation of the controlling system for the switch lock, when applied to a single track railroad, and shown in Figs. 3 and 4, is as follows:—If no train is approaching the switch from either direction, within the limits of control hereinbefore stated, the lock magnet L is energized immediately when the push button PB is operated.

Also, if a train is on the short track section g, the lock magnet L may be immediately energized by operating the push button. These features of the operation are similar to those already explained in connection with the double track application of Fig. 1, excepting that the control circuits are somewhat modified to take care of train movement in both directions.

Suppose, now, a train is approaching the switch from the left, that is, is traveling from left to right, in the direction indicated by the arrow X. When this train is in the track sections c, d, e or f, the lock magnet L cannot be energized until after the interval for which the relay T is set. When this train has passed the switch; however, it no longer prevents energization of the lock magnet L, because of the auxiliary circuits established by the energization of the stick relays S⁸ and S¹⁰. In the case of the relay S⁸ for example, when this relay is energized, the wire 121 is connected direct to N, so that the lock magnet L may be energized, although contact 123 or contact 125 of the track relays of the track sections h and i are open. As previously explained, the stick relay S⁸ is energized when a train passes the signal 8 traveling in the direction of traffic governed by that signal, that is, from left to right, but is not energized when a train travels in the opposite direction. The same features of control apply to train movements in the opposite direction from right to left. In this way, trains approaching the switch from either direction, prevent a release of its electric lock, but trains receding from the switch in either direction, do not prevent such release. It is, of course, evident that after a train has passed the switch and is traveling away from it, there is no longer any occasion to prevent opening of the switch. In all cases when the push button PB is operated, or the switch box contacts opened, the signals 6 and 7 governing traffic toward the switch from both directions are put to stop, thereby blocking all train movements toward the switch.

The modified arrangement shown in Fig. 5 is substantially the same as that illustrated in Figs. 3 and 4, with the difference that the control exerted upon the lock magnet L by trains approaching the switch within certain limits, is obtained from the line relays of signals 8 and 5. For example, the lefthand portion of the energizing circuit for lock magnet L, comprising wires 106, 120, etc., instead of being taken through the several front contacts 116 and 114 and 111 of the track sections c, d and e, as in Figs. 3 and 4, is taken through front contact 150 of line relay H⁵, a shunt for this contact being established when stick relay S⁵ is picked up. This modified construction

obviates the need of extra line wires for any long distance along the track, but may result in extending the limits of control for the lock magnet L further than necessary with certain locations of the siding, as shown in Fig. 5. Referring to Fig. 5, the line relay H⁶ is dropped, as soon as a train enters the stretch of single track, that is, referring to Fig. 3, passes signal 2. Evidently this limit of control is longer than necessary for safety, and may cause useless delays. In other respects, the circuits shown in Fig. 5 are the same as those in Figs. 3 and 4 and have been given the same reference numbers.

Fig. 6 illustrates another modification which is adapted for the protection of a switch lock near yard limits or the entrance to unsignaled territory, or the like, where there are no track circuits. To illustrate the nature of this modification, I have shown it applied to a stretch of single track over which traffic moves in both directions, but it will be evident that the same scheme of control may be applied to a stretch of double track. Referring to Fig. 6, it is assumed that the siding SD of the switch to be protected is located near the first signal K of the block signal territory, the territory to the right of said signal K being assumed to be yard limits or other territory not provided with track circuits. The block guarded by the signal K is divided into track sections n, o and p having track relays 151, 152 and 153 so as to provide a short track section o at the entrance to the sidings SD for the purpose previously explained. A signal J governs traffic in the same direction as the signal K, and an opposing signal M governs traffic in the opposite direction.

The controlling circuit for signal K, in addition to its control in the usual way by the track relays 151-153 of the track sections protected thereby, is also broken at the normally closed contacts 100 of the push button PB when said push button is operated, and at the switch box contact 98 when the switch is opened. Similarly, the controlling circuit for signal M is taken through the normally closed contacts 100 of the push button PB and the switch box contact 98. These controlling circuits are shown in simplified manner to avoid complication.

When a train is on the short track section o, the lock magnet L may be energized when the push button PB is operated by a circuit running from B, push button contacts 102, wire 157, back contact 158 of track relay 152, wires 159 and 160, and lock magnet L to N. In this way a quick release of the electric lock may be obtained when a train pulls up to the switch. If a train is on the siding, and it is desired to open the switch,

the lock magnet L cannot be energized until after the lapse of time for which the time element relay T is set. Release of the lock under these conditions is not dependent upon the location of trains on the main track, as in the previous modifications. This difference is occasioned by the fact that no track circuits exist to the right of the signal K, so that there is a way of telling when a train is approaching within a dangerous distance from the switch. The time element relay T is set into operation when the push button is operated in the same way as already described, and after the time interval has elapsed, contacts 40 of relay T close and establish an energizing circuit for the lock magnet L running from B, contacts 40, wires 161 and 160, and lock magnet L to N. This modified arrangement shown in Fig. 6 permits the safe control of switch locks near the end of block signal territory. Except where a train is about to enter the siding, the release of this switch lock cannot be obtained until after a short interval of time, but since the signals, as K and M, governing traffic on the main track past the switch are put to stop at the beginning of this time interval, full protection is obtained. The same arrangement is applicable to any case where it is not desired to provide an overlap beyond the signals nearest the switch governing traffic on the main track.

According to the present block signaling practice, with which I am familiar, electric switch locks are sometimes used for distant switches near interlocking towers or stations, and the lock is controlled by the operator at said tower or office; but so far as I am aware, it has not been heretofore proposed to provide a switch lock controlled automatically by train movement and manipulated by the trainmen at the switch, because known ways of governing electric locks have not permitted it to be released when safe to do so, while at the same time preventing its release in the face of an approaching train. The present invention, it will be observed, satisfies these conditions requisite to proper protection of switches, the switch lock being controlled in such a way that it may be released and the switch opened under any one of the contingencies occurring in practice, provided that conditions exist or have been set up to prevent a train running into the switch.

While I have shown and described various modifications adapted for both single and double track roads, it should be understood that this specific arrangement of circuits and devices are merely illustrative of the nature and principles of the invention and may be modified or combined by expedients familiar to those skilled in the art, so as to conform to the varying requirements found in practice. I desire to have it under-

stood, therefore, that my invention is not limited to the specific constructions and arrangements shown and described.

What I claim and desire to secure by Letters Patent of the United States is:—

1. In a system for protecting an outlying switch in block signal territory, an electric lock, a normally open releasing circuit for said lock, an electrically operable time element release adapted to close a brake in said circuit after the lapse of a time interval, and manually operable circuit controlling means at the switch for initiating the operation of said relay and for simultaneously governing signals to block train movements over the switch. 70
2. In a system for protecting an outlying switch in block signal territory, an electric lock, a track circuit adjacent to the facing points of the switch, a releasing circuit for said lock including a back contact of the track relay of said track circuit, and a manually operable circuit controller at the switch for closing said releasing circuit at another point. 75
3. In a block signal system for railroads having outlying switches, an electric lock for each switch acting when deenergized to prevent opening thereof, a circuit controlled by track circuits near the switch for energizing said lock, another circuit for energizing said lock, a normally deenergized time element relay adapted when energized to close a break in said another circuit, after the lapse of a time interval, and manually operable means for determining closure of said circuits and for simultaneously causing the blocking of train movement over the switch. 80
4. In a system of the character described, an electric lock, a plurality of normally open releasing circuits for said lock governed respectively by a track circuit adjacent to the switch and a time element relay, and manually operable circuit controlling means adjacent to the switch for closing said circuits. 85
5. In a system for protecting outlying switches, an electric switch lock controlling the switch, a short track circuit at the facing points of the switch, and manually operable means at the switch responsive to the presence of a train on said track circuit for permitting release of the lock, whereby the switch may be unlocked and opened without delay to permit a train on the main track to enter the siding. 90
6. In a system for protecting outlying switches in block signal territory on stretches of single track, an electric lock controlling each switch, a track circuit controlled means responsive to the direction of movement of the trains over certain portions of the track on opposite sides of the switch for governing the release of said lock, whereby the trains approaching the switch from either direction will prevent release of the lock while the trains receding from the switch will not prevent such release. 95
7. In a system for protecting outlying switches in block signal territory on stretches of single track, an electric lock controlling each switch, an energizing circuit for the lock controlled by certain track circuits at one side of the switch, and means effective when a train moves over said track circuits away from the switch for establishing said energizing circuit independently of its track circuit control. 100
8. An electric switch lock for outlying switches having three independent energizing circuits, manually operable circuit controlling means for determining the closure of said circuits, one of the circuits being governed by certain track circuits on one side of the switch, another circuit by a short track circuit opposite the facing points of the switch, and the third circuit by a time element relay, and means whereby said time element relay is set into operation when said circuit controlling means is actuated. 105
9. An electric lock for outlying switches, an energizing circuit therefor, an electrically operable time element relay for closing said circuit, a signal governing traffic on the main track past said switch, and manually operable means at the switch for causing said signal to give its stop indication and for setting said time element relay into operation. 110
10. In combination with an outlying switch in block signal territory, a manually operable locking means for said switch, an electric lock adapted when deenergized to prevent operation of said locking means, an energizing circuit for said lock, signals governing traffic on the main track past the switch, and having controlling circuits, and a manually operable circuit controller at the switch for breaking said controlling circuits and for simultaneously closing the releasing circuit of the electric lock. 115
11. In a system for protecting outlying switches in block signal territory, an electric lock for preventing unlocking of the switch, a releasing circuit for said lock governed by track circuits adjacent to the switch, an alternative releasing circuit for the lock, a time element relay for closing the alternative circuit at one point, and a manually operable circuit controller for simultaneously closing a break in said releasing circuits and for initiating the operation of the time element relay. 120
12. In a system for protecting outlying switches in block signal territory, an electric lock controlling the manipulation of the switch, a plurality of releasing circuits for said lock, one governed by track circuits 125

- adjacent to the switch, a time element relay governing another relay circuit, and a short track section at the facing points of the switch governing a third releasing circuit, 5 signals governing traffic over the switch and having control circuits, and a manually operable circuit controller for opening said control circuits of the signal, initiating the operation of the time element relay, and 10 closing a break in each of the releasing circuits.
13. In a system for protecting outlying switches on stretches of single track, an electric lock, a releasing circuit governed by 15 a track circuit on one side of the switch, and means for independently governing said releasing circuit when a train traveling away from the switch occupies said track circuit.
- 20 14. A system of switch protection for single track railroads, comprising, an electric lock, a releasing circuit therefor, and means associated with track circuits on one side of the switch for governing the releasing circuit dependent on the direction of movement of trains.
- 25 15. A system for protecting switches on single track railroads comprising, the combination with track circuits each having a track relay, a switch, signals governing traffic in both directions toward the switch, an electric lock, and a releasing circuit for said lock including front contacts of said track relays, shunt circuits for said front contacts 30 of the track relays on opposite sides of the switch automatically closed by trains moving away from the switch, and a hand-operated circuit controller at the switch for closing said releasing circuit.
- 35 16. In a signal system, an outlying switch, a switch box connected to the switch points, track circuits on one side of the switch and each having a track relay, a signal governing traffic over the switch and having a control circuit governed by said track circuits, and by contacts of the switch box, an electric lock for the switch, a hand-operated circuit controller at the switch for breaking 40 said control circuit, and a time element relay governing said lock and set into operation by the actuation of said circuit controllers.
- 45 17. In a system of the character described, the combination with an outlying switch and a short track circuit opposite the facing point of the switch and having a track relay, an electric lock, and an energizing circuit for said lock including a back contact 50 for said track relay.
- 55 18. In a signal system, the combination with an outlying switch in a block signal territory, an electric lock, a signal governing traffic over the switch, a control circuit for the signal, a releasing circuit for the electric lock, hand-operated circuit control- 60
- ling means for simultaneously interrupting said control circuit and closing a break in the lock releasing circuit, and a switch box connected to the points of the switch for opening another break in said control circuit when the switch is shifted from its normal position. 70
19. In a system for protecting outlying switches on single track railroads, the combination with a manually operable switch lock, an electrically operable device for preventing release of said lock, and means dependent on the direction of movement of trains for controlling the operation of said device. 75
20. In a single track block signal system, the combination with an electric lock for an outlying switch, a releasing circuit for the lock, and means including a stick relay for governing the releasing circuit dependent upon the direction of movement of trains. 80
21. In a system for protecting outlying switches, an electric lock, the normally opened releasing circuit for the lock, a normally deenergized electrically operable time element device adapted to close said circuit after the lapse of a time interval, and circuit controlling means at the switch for initiating the operation of said time element device. 85
22. In a system for protecting outlying switches in block signal territory, a manually operable switch lock, an electrically operable device for preventing release of said lock, a time element relay adapted to permit energization of said device and release of said lock after the lapse of a time interval, and separate manually operable circuit controlling means at the switch for initiating the operation of the time element relay. 90
23. In a system of the character described, the combination with an outlying switch and an electric lock therefor, a normally inactive electrically operable time element device for controlling the release of said lock, an energizing circuit for the time element device, and a spring-return push button located adjacent to the switch for closing said energizing circuit. 95
24. Means for governing electric locks of outlying switches comprising, a manually operable circuit controller, an electrically operable time element relay, a signal governing traffic over the switch, a control circuit for said signal, and a track circuit controlled releasing circuit for the lock, the operation of the circuit controller simultaneously interrupting said signal control circuit, closing a break in the lock releasing circuit, and initiating the operation of the time element relay. 105
25. In a signal system for single track railroads, an outlying switch, an electric lock therefor, signals governing traffic in both directions toward the switch, govern- 110
- 120
- 125
- 130

- ing circuits for the signals, a releasing circuit for the lock controlled by the track circuits on both sides of the switch, and manually operable circuit controlling means 5 for interrupting said signal control circuits and for simultaneously closing a break in the lock releasing circuit.
26. In a system of the character described, the combination with an outlying switch in 10 block signal territory, manually operable locking means for the switch, an electrically operable device including a lock electro-magnet for preventing operation of said locking means unless said lock electro-mag- 15 net is energized, an energizing circuit for the lock electro-magnet, a signal governing traffic over the switch, a control circuit for the signal, and circuit controlling means for simultaneously interrupting the signal 20 control circuit and closing a break in the energizing circuit for the lock electro-magnet.
27. In a system for protecting outlying switches in block signal territory, manually 25 releasable locking means for the switch including an electro-magnet adapted when de-energized to prevent release of said locking means, a plurality of energizing circuits for said electro-magnet, a time element device 30 for controlling one of said energizing cir- 35 cuits, another energizing circuit being con- trolled by track circuits on one side of the switch, a signal governing traffic toward the switch, a control circuit for said signal, a switch box connected to the switch points 40 for interrupting said control circuit when the switch is displaced from its normal pos- 45 ition, and a manually operable circuit con- troller acting when operated to simultane- 50 ously interrupt said control circuit, initiate the operation of said time element device, and close a break in the track circuit con- 55 trolled energizing circuit for said electro- magnet.
45. 28. A system for controlling electric lock of outlying switch on single track railroads in which trains within a limited distance of the switch and traveling toward it maintain the electric lock in the locked condition, and 60 in which trains within a limited distance of the switch and traveling away from it permit release of the electric lock.
29. In a block signal system for single track railroads, a plurality of signals at in- 65 tervals along a stretch of single track be- 70 tween passing sidings for governing traffic in both directions, track circuit controlled means responsive to the presence of a train in said stretch and its direction of movement 75 for causing the opposing signals to assume the stop position and the signals governing following movements to successively assume their stop and caution positions behind said train, a switch at an intermediate point in 80 said stretch, an electric lock therefor, and re- 85 leasing circuits for said lock governed by, said first mentioned means.
30. In a single track block signal system, the combination with an outlying switch and an electric lock therefor, a signal governing 90 traffic away from said switch, and means as- 95 sociated with said signal and operated auto- matically by a train traveling in the direc- 100 tion of traffic governed thereby for control- 105 ling the release of said electric lock.
31. In a system of the character described, a switch, an electric lock for the switch, an energizing circuit for said lock governed by a plurality of track circuits on one side of 110 the switch, and means including a stick re- 115 lay controlled by two adjacent track circuits of said plurality for independently deter- 120 mining the release of said lock.
32. Means for protecting outlying switches in block signal territory comprising, a 125 switch box connected to the switch points, electrically controlled and manually oper- 130 able locking means for said switch, a lock re- 135 leasing circuit adapted when closed to per- 140 mit manual operation of said locking means, a signal for governing traffic over the switch, a control circuit for the signal governed by 145 said switch box, and a push button having 150 normally closed contacts included in said control circuit, and normally open contacts 155 for governing the lock releasing circuit.
33. In a system for protecting outlying switches in block signal territory equipped 160 with the usual track circuits, the combina- 165 tion with two signals governing traffic to- 170 ward the switch and automatically con- 175 trolled by the intervening track circuits, a 180 control circuit for said signals adapted whenever interrupted to cause said signals to 185 indicate stop and caution respectively, 190 electrically controlled locking means for the 195 switch, a releasing circuit for said locking 200 means controlled by at least all of the track 205 circuits between the switch and the signal 210 farthest therefrom, slow acting means 215 adapted to permit release of the locking 220 means after an interval of delay independ- 225 ently of said releasing circuit, and manually 230 operable means at the switch for interrupt- 235 ing said control circuit, for closing a break 240 in said releasing circuit, and for initiating 245 the operation of said slow acting means.
34. In a system for protecting outlying switches in block signal territory, two sig- 250 nals governing traffic toward the switch and 255 having a control circuit adapted if inter- 260 rupted to cause said signals to indicate stop 265 and caution respectively; a switch circuit 270 controller connected to the switch points 275 and having contacts opened if the switch is 280 displaced from its main line position, said 285 control circuit including said contacts; 290 manually operable and electrically con- 295 trolled locking means at the switch for pre- 300 venting movement of its points; a releasing 305

circuit adapted if closed to permit operation of said locking means to unlock the switch, said releasing circuit being controlled at least by all of the track circuits between the switch and the signal farthest therefrom and by one track circuit in the rear of said farthest signal; an electrically operable time element device adapted to permit release of said locking means after an interval of time

independently of said releasing circuit; and manually operable means at the switch for simultaneously breaking said control circuit for the signals, closing a break in said releasing circuit, and initiating the operation of said time element device.

In testimony whereof I have affixed my signature.

SEDGWICK N. WIGHT.
